UNITED STATES PATENT OFFICE

EVERETT B. CUSHMAN, OF LANSING, MICHIGAN, ASSIGNOR, BY MESNE ASSIGNMENTS, TO FOOD MACHINERY CORPORATION, OF LANSING, MICHIGAN, A CORPORATION OF DELAWARE

CARBURETING APPARATUS

Application filed July 24, 1924. Serial No. 727,862.

This invention relates to the reservoiring of fuel oil and carburetion of air in connection with internal combustion engines. It is especially designed for stationary engines, but might be used with a boat or automobile engine.

It is the object of the invention to lift the fuel oil from a comparatively lower level to the cylinder ports by means of the engine suction, without the intervention of special vacuum apparatus, which is relatively costly, complicated and liable to get out of repair.

The apparatus is so designed that the raw fuel is lifted only a small distance; it is then aspirated and mixed with a small quantity of air in such a rich state as to be non-combustible. It is then lifted in an atomized condition to the level of the cylinder ports and there mixed with the proper amount of air to be combustible.

Referring to the drawings:

Fig. 1 is a side elevation of an engine equipped with my improved apparatus.

Fig. 2 is a vertical cross section showing the apparatus.

Fig. 3 is an enlarged cross section of the screen in the bottom of the fuel oil pipe.

a represents an internal combustion engine provided with the usual manifolds, spark plugs, wiring and other accessories and parts, which are obvious from an inspection of the drawings. A liquid fuel reservoir is here shown as formed in the stand *a*, upon which the motor is supported. This is a convenient form for a power unit which is stationary; however, the reservoir might be at any low point. Supported on this stand is a fixture *b* in the nature of a carburetor, but so carbureting the air as to make it non-combustible due to the large excess of hydro-carbon over the air as compared with a normal combustible mixture. This fixture is provided with a venturi, a nozzle *d*, needle control valve *e*, valve controlled air intake *f*. Preferably this air intake is connected by a pipe *h* with air intake *g* of the upper fixture, later to be described. This permits the use of a single air filtering device where this is desired. The Venturi tube *c* is connected by a riser tube *i* with the upper fixture *j* which

is a casting and in which is located the throttle valve *k* which is here shown as controlled by a governor roller *m*, as is common in stationary engine practice, but obviously might be controlled in any other suitable way, as by hand. *n* is a priming cup, while *q* designates a spring closed supplemental air port.

Of course, it is not new to have the spring controlled supplemental air ports which open at a high engine suction for the purpose of diluting the charge, but in most carburetors where such supplemental air valves are used, they are simply used to further dilute an already combustible mixture at high engine speeds. Here the purpose of the supplemental air intake is to get a final correct air and oil proportion to the mixture at substantially the level at which the same is used, while the aspirating air which is taken in at a relatively much lower level is used primarily for the purpose of forming a light vehicle which can serve to lift the fuel oil to a relatively much higher level by the aid only of the engine suction from the carbureting apparatus.

In Fig. 3 I have shown a check valve, or what I term, a foot valve on the bottom of the pipe or conduit which leads to the bottom of the fuel tank and carries the fuel oil to the nozzle. This valve obviously maintains a column of fuel oil at all times within the pipe regardless of the level of the liquid in the tank, resulting in substantial uniformity of performance at all times regardless of the level of the fuel oil in the tank.

What I claim is:

1. In a carbureting and fuel oil lifting apparatus for internal combustion engines arranged to connect an oil reservoir with the intake ports of the engine cylinders, the combination of a fuel oil reservoir, a lower fixture having a relatively large single conduit connection to said reservoir and provided with a fuel oil nozzle and aspirating air inlet to afford a relatively rich mixture which is practically non-combustible, the said fixture being located near the level of said reservoir and said conduit having a foot valve at the bottom thereof, an upper fixture located near

the level of the cylinder ports for providing additional air to convert the practically non-combustible mixture furnished by the lower fixture into a combustible mixture, a fuel supply conduit and an air supply conduit connecting the two fixtures, suction means operating to lift the fuel oil to the level of the fuel nozzle in its raw state and operating to lift the atomizing fuel oil and aspirating air from the lower fixture to the level of the higher fixture, the said upper fixture provided with a throttle valve to control the gases passing into the engine and with a suction controlled valve for governing the admission of additional air to make the lifted non-combustible mixture, combustible for use in the engine.

2. In a carbureting and fuel oil lifting apparatus for internal combustion engines arranged to connect an oil reservoir with the intake ports of the engine cylinders, the combination with a fuel oil reservoir, of a lower fixture having a conduit having an inlet opening near the bottom of said reservoir and provided with a fuel oil nozzle and an aspirating air inlet to afford a relatively rich mixture which is practically non-combustible, the said fixture being located near the level of said reservoir, an upper fixture located near the level of the cylinder ports for providing additional air to convert the practically non-combustible mixture furnished by the lower fixture into a combustible mixture, an up-going conduit connecting the two said fixtures for carrying upwardly the non-combustible mixture, and a down-going conduit connecting the two fixtures for carrying air taken into the upward fixture to the lower fixture to afford the aspirating medium.

3. In a carbureting and fuel oil lifting apparatus for internal combustion engines of the type adapted to lift liquid fuel in a non-combustible state to a certain point before changing the same to a combustible fuel, the combination with a fuel oil reservoir, of an integral lower fixture positioned adjacent said oil reservoir, and an upper integral fixture located adjacent the cylinder ports of the internal combustion engine, a single conduit of relatively large diameter extending from said lower fixture to a point adjacent the bottom of said fuel reservoir, a foot valve connected to the end of said single conduit for maintaining a substantially constant level of fuel in said conduit, a single conduit extending from said lower fixture to said upper fixture for conducting a relatively rich mixture of liquid fuel in a practically non-combustible state from said reservoir to said upper fixture, suction means operating to lift the fuel oil to said second fixture, and said second fixture including a suction-controlled air valve to govern the introduction of air necessary to produce proper combustion, an aspirating air inlet and a fuel oil

nozzle located in said first fixture, means positioned in said first fixture for regulating the flow of liquid fuel from said first named single conduit to said nozzle, and a second conduit connecting said two fixtures for conducting air from said upper fixture to the lower fixture.

In testimony whereof I have affixed my signature.
